WRIST MECHANISM FOR ARTIFICIAL ARMS

Karl C. Vesper, Santa Monica, Calif., assignor to
A. J. Hosmer Corporation, Santa Monica, Calif.,
a corporation of California

Application December 5, 1947, Serial No. 789,801

5 Claims. (Cl. 3—12.4)

1

My invention relates to prosthetic devices and particularly to an artificial arm for use by "above-the-wrist" amputees and having a forearm to which a hand is connected. Specifically, the invention pertains to an improved wrist structure for detachably connecting the hand to the forearm and to center-controlled means for actuating the grasping hook or finger of the prosthetic hand.

It is desirable, in artificial arms of the class referred to, that different types of grasping hooks be used at the will of the amputee to perform various functions. For example, when the arm is not used to perform work, an artificial hand closely resembling a human hand in appearance, but having stationary fingers, may be employed. However, when the arm is to be used to perform work, such as lifting objects, it is necessary that either a hand having movable fingers or jaws or a prosthetic device having one hook or a pair of movable hooks be employed so that the objects can be grasped between the jaws or hooks and lifted by the arm when the latter is flexed at the elbow. It is therefore desirable that the wrist portion of the arm be constructed in a manner such that it is capable of connecting various types of hands to the end of the forearm. To provide for maximum utility of the hand and to adapt it to perform certain operations, it is necessary that the hand be connected in such manner that it can be turned with respect to the forearm to obtain full pronate, supination action. Moreover, it is highly desirable that the hand be capable of closing and opening in order to adapt it to grasp and release objects.

It is a primary object of my invention to provide a prosthetic arm which meets all the prerequisites enumerated above so as to make the arm more universal in use. It is an important object in this respect to provide an artificial arm in which is embodied an improved wrist joint capable of releasably connecting or locking a hand member to the end of the forearm such that the hand member is positively retained in place to resist considerable force which might tend to disconnect the same. In its preferred form, the hand retaining means includes a releasable latch which is adapted to engage in a peripheral groove in the shank of the hand member so as to effectively retain the hand member connected to the forearm while permitting relative rotation or angular adjustment between the forearm and hand member in both pronate and supinate directions, and this is another object of the invention.

It is a further object of the invention to pro-

2

vide a wrist device embodying means for retaining the hand member in different positions of angular adjustment. In accordance with a preferred construction, this means consists of one or more brake shoes which are movable radially within the wrist device and which are adapted to engage the periphery of the inserted shank of the hand member to frictionally resist turning thereof.

10 Another object of the invention is to provide a wrist device which includes two main elements, one element being rigidly secured to the end of the forearm and the other element being rotatable on the rigid element, the rotary element being provided with cam means adapted, upon rotation of the element in one direction, to apply the brake shoes to the shank of the hand member and operative, when rotated in the opposite direction, to permit release of the brake to effect 20 free rotation of the hand member.

It is a further object to provide a wrist device, of the type referred to, in which the latch is carried by and pivoted on the rotary element and to provide means whereby the latch is pivoted to 25 locking position upon rotation of the rotary element toward brake-applying position and pivoted to unlocking position upon rotation of the rotary element to and beyond brake releasing position so that the brake is released prior to the unlocking of the hand member. By this improved construction, the operations of locking and unlocking the hand member and applying and releasing the brakes are accomplished by the simple act of rotating the rotary element in either direction. This is a very desirable feature 35 since it permits convenient and quick locking and unlocking of a hand member without requiring tightening and loosening of screws or other detachable fastening means commonly employed for such purposes. Moreover, by this improved structure the hand members can be readily interchanged and may be angularly adjusted without releasing the retaining means so that the adjustment can be made with the hand directed downwardly without causing disconnection 40 thereof.

Another object is to provide a wrist device in which the several parts are held in assembled relationship by means of a single element, namely, 50 the latch which retains the hand member connected to the wrist, the latch being carried by the rotary element of the device and normally engageable with the fixed element of the device but adapted to be moved to disengage 55 the fixed element so as to permit separation of the two elements. Thus the wrist device may

be assembled and disassembled by merely actuating the latch and it is apparent that this makes for simplicity of operation and greater economy of manufacture since it eliminates screws, rivets and other fastening means which would be inserted during the assembly of the parts.

In addition to the features outlined above, the present invention has for another object the provision of hydraulic means incorporated in the wrist device for voluntarily actuating one or both of the fingers or jaws of the artificial hand. In its preferred construction, the hydraulic means consists of a cylinder within the wrist structure and a piston slideable in the cylinder and having an outer extension or stem operatively connected to at least one of the movable jaws, said stem being adapted when fluid pressure is exerted against the piston, to relatively shift the jaws toward and away from each other to permit the jaws to embrace an object to be grasped therebetween and to cause opening of the jaws to release the object at the will of the amputee.

Various types of artificial hands have been employed in the past and it is the usual practice to operate the movable fingers or hooks thereof by means of cords or cables arranged externally of the arm and connected to a shoulder harness so as to be pulled in response to a shrug of the shoulder. Such exposed cables are apt to catch against the clothing of the wearer and are otherwise inefficient for other reasons. It is therefore an important object of the present invention to provide a combination wrist and hand structure in which the fingers or hooks are operated by a so-called "center control" wherein the remotely controlled means for operating the hooks is movable within the wrist and, in the case of an above-the-wrist amputee, through the artificial forearm. By this construction and arrangement of parts, the hook or hooks can be operated either by a cable or by hydraulic means movable entirely within and centrally of the wrist and forearm, and one or a plurality of the fingers or hooks can be actuated by the single actuating means.

Further objects of my invention will be apparent from the following specification and the drawings, which are intended for the purpose of illustration only, and in which:

Fig. 1 is a side view of an artificial arm embodying the features of the invention, the wrist device being shown in section to disclose the internal structure thereof;

Fig. 2 is an enlarged longitudinal section, taken on line 2—2 of Fig. 1;

Fig. 3 is an enlarged cross-sectional view taken on line 3—3 of Fig. 1 showing the brake means released;

Fig. 4 is a view similar to Fig. 3 but illustrating the brake means applied;

Fig. 5 is a longitudinal sectional view through a wrist device of modified construction, in which a pair of fingers or hooks is actuated simultaneously; and

Fig. 6 is a side view of an alternative structure in which the movable finger or hook is moved to operative position by means of a control cable.

Referring first to Figs. 1 to 4 of the drawings, my improved wrist structure is shown as applied to use in a prosthetic arm consisting of a tubular forearm 5 of conventional shape and a hand 6 detachably connected to the forearm by means of the present wrist device 7. The forearm 5 may be provided with hinge straps 8 for use in connecting it to an upper arm (not shown) when

the artificial arm is used by above-the-elbow amputees, but in cases where the arm is used by above-the-wrist amputees the upper hinge portion is dispensed with and the forearm made in the form of a socket for receiving the lower end of the forearm stump to which it may be attached by any known means. The forearm 5 may be constructed from moldable plastic or other material and held in its lower end is an insert or socket member 10.

The socket member 10, which constitutes one of the main elements of the improved wrist device 7, is annular in outline and has a rearward portion 11 adapted to fit into the lower end of the forearm 5. Preferably, the end 11 of the socket member 10 is molded into the end of the forearm to provide a permanent connection therebetween. The socket member 10 has annular wall 12 disposed midway between its ends and projecting forwardly from this wall is a sleeve portion 13 having a bore or socket 14. An annular space or recess 15 is provided between the outer circular wall 16 and the periphery of the sleeve portion 13.

Forwardly of the wall 12 the sleeve portion 13 is provided with a pair of diametrically opposite rectangular openings 17 in which friction elements or brake pads 18 are adapted to slide radially toward and away from the axis of the socket member 10. The brake pads 18 may be constructed from fiber, leather or other suitable material and, as shown in Fig. 3, are riveted to brake shoes 19. The shoes 19 have lateral projections 20 and their outer ends are provided with obtuse points 21. Leaf springs 22 have their ends engaged under the projections 20 of the opposite shoes 19 and tend to urge the shoes radially outward, the springs being capable of flexing or bowing, however, so that the shoes can be forced inwardly by means to be presently described. The sleeve portion 13 is also provided with a slit 23 (Figs. 1, 3 and 4) through which a latch, to be later described, is adapted to move.

A pair of semi-circular grooves or recesses 27 is provided in the inner surface of the wall 16 of the socket member 10 at diametrically opposite locations, the recesses being disposed adjacent the pointed ends 21 of the brake shoes 19. In the recesses 27 are pivotally mounted the rounded ends 28 of a pair of arcuate brake levers 30 which extend alongside the inner surface of the wall 16, each extending through substantially ninety degrees, the free ends of the levers being beveled.

The rotatable element of the wrist device comprises an annular cap 31 which has a circular wall 32, an inner annular flange 33 and an outer annular wall 34. The inside diameters of the flange 33 and wall 34 are such that the cap member 31 may be slid axially onto the sleeve portion 13 to adapt it to rotate thereon. The cap member 31 is provided on its rearward face with a pair of diametrically opposite cams 35 of semi-crescent shape. The outer curved surfaces of the cams 35 are concentric with the axis of the cap member 31 to adapt them to fit within the annular recess 15 and to rotate against the wall 16 of the socket member 10. When the cap member 31 is rotated in counterclockwise direction, as viewed in Figs. 3 and 4, the thin leading ends of the cams 35 will engage the beveled ends of the brake lever 30 and continued rotation of the cap member will cause the cams to pivot the levers inwardly as shown in Fig. 4. Through the engagement of the levers 30 with the outer

pointed ends of the brake shoes 19, the latter are slid inwardly.

Disposed against the outer surface of the inner annular flange 33 of the cap 31, and pivoted on a pin 37 extending between the flange and the outer annular wall 34, is a latch member 38. The latch member 38 has a curved end portion 39 and a curved finger-piece 40 projecting laterally from the end of the curved portion and positioned in a rectangular aperture 41 in the circular wall 32 of the cap member 31. The latch member 38 is normally pivoted in counterclockwise direction, as viewed in Figs. 3 and 4 under the action of a spring 42 coiled around the pin 37 and having one of its ends bearing against the circular wall 32 of the cap member and its other end hooked across the edge of the latch member. Pivotal movement of the latch member 38 toward the axis of the cap member 31 is limited by the engagement of a tail piece 43 of the latch member 38 against the inner surface of the circular wall 32.

The hand member 6 includes a body portion 45 having a claw-like finger or hook element 46 projecting from one end thereof, the interior surface of the element being preferably lined with rubber or other resilient material 47. At its opposite end, the member 6 is provided with a tubular extension or shank portion 48 having an outside diameter slightly smaller than the bore 14 of the sleeve portion 13 of the socket member 10 to adapt the shank portion to be inserted therein and the hand member to rotate with respect to the forearm 5. The shank portion 48 is provided with a peripheral groove 50 in which the curved end portion 39 of the latch member 38 is adapted to engage to releasably retain the hand member in place.

To apply a hand member 6 to the end of the forearm 5, the cap member 31 is rotated in clockwise direction and eventually the latch member 38 will engage an end 23' of the slit 23 of the sleeve portion 13 and thus be cammed outwardly against the action of the spring 42 to the position indicated by dot-and-dash lines in Fig. 3. At the same time the cams 34 will be moved from engagement with the brake levers 30 so that the brake shoes 19 are free to move radially outward under the influence of the leaf springs 22. The interior of the sleeve portion 13 is thus free of obstructions and the shank portion 48 of the hand member 6 may be inserted thereinto as shown in Figs. 1 and 2, with the body portion 45 abutting the outer surface of the cap member 31. The insertion of the shank portion 48 by the normal or sound hand of the amputee is greatly facilitated if the forearm 5 is held with the wrist device 7 uppermost.

After the hand member 6 has been applied in the above manner, the cap member 31 is rotated in reverse or counterclockwise direction to a slight extent to cause the latch member 38 to move away from the end 23' of the slit 23. At this juncture, the spring 42 acts to swing the latch member 38 inwardly to the position shown by full lines in Fig. 3 whereupon its curved end portion 39 moves through the slit end into the peripheral groove 50 of the shank portion 48 and thus serves to retain the shank portion within the wrist device 7 while permitting rotation of the hand member 6.

It is desirable that the hand member be held in different positions of angular adjustment with respect to the forearm and this is particularly true when so-called "work hands" are employed. With the artificial arm lowered, the amputee

turns the hand member 6 to any desired position, and thereafter rotates the cap member 31 to a further extent in counterclockwise direction. During this additional rotation, the latch member 38 remains engaged in the peripheral groove 50 and the cams 35 move under the brake levers 30 to pivot the latter inwardly as shown in Fig. 4 so that the brake shoes 19 are moved radially inward to cause their friction pads 18 to engage the periphery of the shank portion 48 to prevent rotation of the hand member 6 with respect to the forearm 5. It is thus seen that the hand member 6 is effectively retained within the wrist device 7 by the latch member 38 and held against rotation by the brake pads 18. To remove the hand member so that other types of hands may be applied to the forearm, the operation is reversed, that is, the cap member 31 is rotated in clockwise direction to first release the brakes and thereafter disengage the latch member 38 from the peripheral groove 50 of the shank portion 48 to permit withdrawal of the hand member.

Work hands of the type shown in Fig. 1 are commonly provided with a finger or hook 55 which is movable toward and away from the fixed hook 46 to enable the amputee to grasp objects between the two hooks and to release the same therefrom. The upper end of the finger 55 is preferably located within a slot 56 in the body portion 45 and is pivoted on a transverse pin 56' extending across the slot. The finger 55 may have a rubber pad 57 on its inner surface. The finger or hook 55 is normally pivoted to closed position against the fixed jaw 46 by means of a coil spring 58.

It is desirable that the hook 55 be pivotally moved to open position by manually controlled means, and the present invention contemplates the provision of fluid actuated means for effecting such movement. Referring to Figs. 1 and 2, the movable hook 55 is provided with an offset lug 60 which is positioned in alignment with the axis of the shank portion 48. Screwed into the upper end of the socket member 10 is a disc 61 which carries a fluid cylinder 62, the cylinder being closed at its upper end by a sealed plug 63. The cylinder 62 extends down into the shank portion 48 and has a sealed lower end. Adapted to slide vertically in the cylinder 62 is a piston 65 provided with an axial stem 66, the lower end of which engages the offset lug 60 of the pivoted hook 55. Hydraulic fluid may be introduced into the upper end of the cylinder 62 and into the hollow piston 65 by means of a hydraulic line 67 passing through holes in the disc 61 and plug 63. The upper end of the hydraulic line 67 may be connected to any suitable pressure creating means which may be operated in response to movement of an arm, shoulder or other part of the torso of the wearer. When hydraulic fluid is forced into the cylinder 62, the piston 65 is moved downwardly to swing the pivoted hook 55 away from the fixed hook 46 and when the pressure of the fluid is relieved, the spring 58 returns the pivoted hook to closed position.

Referring now to Fig. 5, the present invention contemplates the provision of a combination wrist and hand structure 60 in which the fingers or hooks 61 and 62 are adapted to be pivoted toward and away from each other to grasp and release various objects. This alternative structure is adapted to be applied to the end of a forearm member 63 and, as in the embodiment previously described, the structure includes a

socket member 64, an annular cap member 65 rotatable about the axis of the socket member, braking means 66 and a latch member 67. Screwed into the upper threaded end of the socket member 64 is a cylinder member 69 which has a lower axial extension 70 disposed within the socket member and defining therewith an annular opening 71, and an upper axial extension 72. The cylinder member 69 has an axial bore 73 extending throughout the greater part of its length and in the upper end of the extension 72 is a counterbore providing a cylinder 74, the upper end of the cylinder being closed by a plug 75 screwed thereinto and having a small vent orifice 76. Slidable within the cylinder 74 is a piston 77 which has an integral rod 78 adapted to slide in the bore 73 and carrying a pin 79 adjacent its lower end. Hydraulic fluid is adapted to be introduced into the lower end of the cylinder 74 through a port 80 in which the end of a hydraulic line 81 is held.

A hand member indicated generally at 83, has a tubular portion 84 adapted to be received in the annular opening 71 and to be retained therein by means of the latch member 67. The hand member 83 also has a disc portion 85 which abuts the outer surface of the cap member 65 when the hand member is attached to the wrist device. The hand member 83 has a pair of spaced ears or flanges 86 between which are pivotally mounted, on transverse pins 88 and 89, the pair of hook members 61 and 62. Springs 92 and 93, coiled around the respective pins 88 and 89, each have one of their ends resting against the disc portion 85 and their other ends engaging the hook members 61 and 62. The springs 92 and 93 function to normally pivot the hook members away from each other to the open position shown by full lines in Fig. 5 so as to adapt them to receive an article to be grasped therebetween.

The hook members 61 and 62 may be of any desired shape and at their upper ends they are provided with integral, slotted lugs 94 and 95, respectively, which are positioned at opposite sides of the lower end of the piston rod 78 to receive the pin 79 which operatively connects the hook members to the piston rod.

Assuming that the hook members 61 and 62 are held in the position shown in full lines by the springs 92 and 93, the hook members may be drawn together to clamp an object therebetween by merely swinging them toward each other. To effect such pivotal movement of the hook members 61 and 62, hydraulic fluid is forced into the lower end of the cylinder 74 to cause the piston 77 and its rod 78 to be slid upwardly. The hydraulic line 81 may be connected to a compressible bulb or other manually operable device which acts to force fluid through the line and into the cylinder. As the piston rod 78 is drawn upwardly, it acts through its pin 79 and the lugs 94 and 95 to pivot the hook members 61 and 62 toward each other, in the manner indicated by dot-and-dash lines, so as to cause them to grasp the object therebetween. When fluid pressure is reduced in the lower end of the cylinder 74, the springs 92 and 93 act to return the hook members 61 and 62 to open position and move the piston 77 to lowermost position.

Referring now to Fig. 6, the present invention contemplates a combined wrist and hand structure 100 of further modified construction. As in the previous embodiments, the structure 100

is adapted for attachment to the end of an artificial forearm 101. The alternative structure shown in Fig. 6 is similar to that disclosed in Figs. 1 to 4 except that mechanical operating means is substituted for the hydraulic means thereof. The hand member 102 shown in Fig. 6 includes a fixed hook member 104 and a hook member 105 pivoted on a pin 106 to adapt it to pivot toward and away from the fixed hook member. A spring 107 having its ends engaging the hand member 102 and the hook member 105, respectively, normally functions to pivot the hook member 105 to open position shown. The hook member 105 has a lug 108 to which is attached one end of a cord or cable 109, the cable passing upwardly through the center of the wrist device and forearm and being suitably connected to a shoulder harness or any other appliance capable of being operated by the amputee. When the cord 109 is pulled upwardly, the hook member 105 is pivoted to closed position to clamp an object between this member and the fixed hook member 104. When the cord 109 is released, the spring 107 returns the hook member 105 to open position.

While I have herein shown and described my improved artificial arm as embodied in several preferred forms of construction, by way of example, it will be apparent that further modifications might be made therein without departing from the spirit of the invention. Consequently, I do not wish to be limited in this respect, but desire to be afforded the full scope of the appended claims.

I claim as my invention:

1. In a prosthetic device of the class described comprising a cooperating artificial limb proximal member and an artificial limb terminal member, one of said members having an annular groove extending transversely of and substantially coaxial with the pronation-supination axis, a latch carried by the other of said members and disposed in said groove connecting said members against axial displacement with complete freedom for relative rotary adjustment about said pronation-supination axis, said latch being retractable from said groove for completely disconnecting said members to permit separation thereof, friction brake means carried by said other of said members for retarding relative rotary movement of said members about the pronation-supination axis with any desired degree of resistance from its release position affording complete freedom of relative rotary movement to its fully applied position for effectively locking said members from said relative rotary movement, means operable at an infinite number of positions of relative rotary movement of said members for controlling the effectiveness of said brake means to any desired degree through any increment of said relative rotary movement, hydraulically operable extensible means carried by said proximal member and substantially encompassed by said annular groove for extension substantially parallel to said pronation-supination axis, and pressure responsive means carried by said proximal member and responsive to extension of said extensible means for actuating said terminal member.

2. In a prosthetic device of the class described comprising a cooperating artificial limb proximal member and an artificial limb terminal member, one of said members having an annular groove extending transversely of and substantially coaxial with the pronation-supination axis,

a latch carried by the other of said members and disposed in said groove connecting said members against axial displacement with complete freedom for relative rotary adjustment about said pronation-supination axis, said latch being retractible from said groove for completely disconnecting said members to permit separation thereof, friction brake means carried by said other of said members for retarding relative rotary movement of said members about the pronation-supination axis with any desired degree of resistance from its release position affording complete freedom of relative rotary movement to its fully applied position for effectively locking said members from said relative rotary movement, means operable at an infinite number of positions of relative rotary movement of said members for controlling the effectiveness of said brake means to any desired degree through any increment of said relative rotary movement, hydraulically operable extensible means carried by said proximal member and substantially encompassed by said annular groove for extension toward said terminal member substantially parallel to the pronation-supination axis, displaceable abutment means carried by said terminal member and responsive to extension of said extensible means for actuating said terminal member.

3. In a prosthetic device of the class described comprising a cooperating artificial limb proximal member and an artificial limb terminal member, one of said members having an annular groove extending transversely of and substantially coaxial with the pronation-supination axis, a latch carried by the other of said members and disposed in said groove connecting said members against axial displacement with complete freedom for relative rotary adjustment about said pronation-supination axis, said latch being retractible from said groove for completely disconnecting said members to permit separation thereof, friction brake means carried by said other of said members for retarding relative rotary movement of said members about the pronation-supination axis with any desired degree of resistance from its release position affording complete freedom of relative rotary movement to its fully applied position for effectively locking said members from said relative rotary movement, rotary means for controlling said brake means and said latch, means responsive to rotary movement of said rotary means through one portion of its rotary movement for controlling said latch from and between its disengaged position and its position of engagement in said groove, means responsive to rotary movement of said rotary means beyond said one portion of its rotary movement for controlling the action of said brake means between its release position and its fully applied position at any of an infinite number of positions of relative rotary adjustment of said members, hydraulically operable extensible means carried by said proximal member and substantially encompassed by said annular groove for extension substantially parallel to said pronation-supination axis, and abutment means carried by said terminal member and responsive to extension of said extensible means for actuating said terminal member.

4. In a prosthetic device of the class described comprising a cooperating artificial limb proximal member and an artificial limb terminal member, one of said members having an annular groove extending transversely of and substantially coaxial with the pronation-supination axis, a latch

carried by the other of said members and disposed in said groove connecting said members against axial displacement with complete freedom for relative rotary adjustment about said pronation-supination axis, said latch being retractible from said groove for completely disconnecting said members to permit separation thereof, friction brake means carried by said other of said members for retarding relative rotary movement of said members about the pronation-supination axis with any desired degree of resistance from its release position affording complete freedom of relative rotary movement to its fully applied position for effectively locking said members from said relative rotary movement, rotary means for controlling said brake means and said latch, means responsive to rotary movement of said rotary means through one portion of its rotary movement for controlling said latch from and between the disengaged position and its position of engagement in said groove, and means responsive to rotary movement of said rotary means beyond said one portion of its rotary movement for controlling the action of said brake means between its release position and its fully applied position at any of an infinite number of positions of relative rotary adjustment of said members.

5. In a prosthetic device of the class described comprising a cooperating artificial limb proximal member and an artificial limb terminal member, one of said members having an annular groove extending transversely of and substantially coaxial with the pronation-supination axis, a latch carried by the other of said members and disposed in said groove connecting said members against axial displacement with complete freedom for relative rotary adjustment about said pronation-supination axis, said latch being retractible from said groove for completely disconnecting said members to permit separation thereof, friction brake means carried by said other of said members for retarding relative rotary movement of said members about the pronation-supination axis with any desired degree of resistance from its release position affording complete freedom of relative rotary movement to its fully applied position for effectively locking said members from said relative rotary movement, means tending to retract said friction brake means to its release position, means urging said latch into said groove, rotary means operable successively in one direction of rotary movement for releasing said brake means and then for retracting said latch from said groove, said rotary means being operable successively in the opposite direction of rotary movement thereof for releasing said latch for lodgment thereof in said groove under the influence of said means for urging said latch into said groove and then upon further rotation for applying said brake means with progressively increasing effectiveness as the rotary movement continues, hydraulically operable extensible means carried by said proximal member and substantially encompassed by said annular groove for extension toward said terminal member substantially parallel to the pronation-supination axis, and abutment means carried by said terminal member and responsive to extension of said extensible means for actuating said terminal member.

KARL C. VESPER.
